Patented Mar. 16, 1920.

UNITED STATES PATENT OFFICE.

EDWARD S. COFFMAN, OF CLIFTON FORGE, VIRGINIA, ASSIGNOR TO FRANK E. STEBBINS,
OF WASHINGTON, DISTRICT OF COLUMBIA.

COMBINED CONTRACTILE SPRING AND RETARDING DEVICE.

1,333,835.

Specification of Letters Patent. Patented Mar. 16, 1920.

Application filed April 4, 1917, Serial No. 159,829. Renewed February 8, 1919. Serial No. 275,850.

To all whom it may concern:

Be it known that I, EDWARD S. COFFMAN, a citizen of the United States, residing at Clifton Forge, in the county of Alleghany and State of Virginia, have invented a certain new and useful Combined Contractile Spring and Retarding Device; and I do hereby declare the following to be a full, clear, and exact description of the invention, such as will enable others skilled in the art to which it appertains to make and use the same.

The present application is in part a continuation of my applications filed respectively on November 6, 1909, Serial No. 526,602, and February 12, 1913, Serial No. 747,933; said latter application being in part a continuation of my application filed December 30, 1909, Serial No. 535,672.

The main object or purpose in mind in making the invention was the provision of a combined contractile helical spring and retarding device which should be of compact dimensions, relatively simple and cheap in first cost, durable and not liable to become inoperative thus obviating repairs, easy to manipulate, and effective in its automatic operation. A further object was the provision of regulative retarding means for such a device.

Devices of this general character known and tried and similar ones constructed by me, in which the expansive energy of a spring was relied upon to perform the automatic work were found to be incapable of effective operation, and very unsatisfactory for other reasons when the attempt was made to remedy their defects.

Consequently, and after extended experiments, I devised a novel combined contractile helical spring and regulative retarding device, effectively attaining the ends above recited, by combining with suitable telescopic body members provided with a substantially closed variable air chamber and having an adjustable valve for controlling the quantity of air in the chamber when the members telescope together, a compact helical spring concealed within the members and having its opposite ends positively secured to the opposite members, so that when contracted or slightly under tension the spring

would hold the members together, and also that when expanded with the outward telescopic movement of one member relative to the other the contractile energy of the spring would automatically return the extended member to its seat, a simultaneous checking and retarding effect upon the spring and member in their movements being secured corresponding to the variation of the quantity of air in the chamber controlled and regulated by the adjustable valve.

Accordingly my invention consists in a combined contractile spring and positive retarding device having novelties of construction and combined parts substantially as herein set forth and claimed.

The accompanying drawing illustrates two examples of the embodiment of the invention, slightly different in details, constructed and the parts combined according to the best modes of procedure I have so far devised for the purpose, also one example of the use of the device; it being understood that the same is designed for actuating various movable things or parts, hinged or otherwise, or in connection with machines or structures, with which the device may be operatively combined or associated, for example, to return a valve to its seat, or return a reciprocating carrier.

Figure 1 is a longitudinal sectional view in elevation of the combined device, except a small portion shown in full exterior elevation.

Fig. 2 is a similar view of another example, the contractile spring and its attachments being shown in elevation and other parts in longitudinal section.

Fig. 3 is a cross section of Fig. 2 on line 3-3.

Fig. 4 shows in elevation view a type of the device applied for use in connection with a vehicle frame and a semi-elliptic spring.

The synthetic combination, shown by each of the examples, may be analyzed into abstract parts and identified as follows:

In the example shown by Fig. 1 the letter A designates an exterior hollow body member, in this instance a metallic tube, provided with exterior threads 1 and 2 at opposite ends; B, a substantially closed head at one end having threads 3 matching the

threads 1; and C a head at the opposite end with threads 4 matching the threads 2 of the tube, and provided with a central opening 5 constituting a bearing. The head B 5 has an eye D brazed to the head.

E designates an interior hollow body member, in this instance a metallic tube, provided with exterior threads 9 and slots 10 at the left hand end and with threads 11 at 10 the other end on the exterior surface, said tube being located and movable within the opening 5 in head C and projecting beyond the said head so it can be attached.

F designates a threaded closure for the 15 projecting end of tube E. In the form of a cap it screws on the threads 11.

On the inclosed threaded end of member E is a hollow piston or plunger comprised of a hollow threaded ring or washer 20 13, a cup-shaped flexible packing 14 of leather or other suitable material, and a threaded follower or clamping ring 15, the cup packing facing the head B and adapted frictionally to engage the interior surface 25 of member A and form a tight joint when subjected to greater than atmospheric pressure, but which packing can yield and allow air to pass from the space back of it to the space in front of it. The ring 13 30 is of slightly less diameter than the tube A so as to provide a small open space 16 for the passage of air or fluid downwardly and between the packing and inner surface of the exterior member.

35 S is a contractile helical spring located mainly within the interior tubular member when seated, the spring normally being slightly under tension, as shown, and secured at one end to the eye D on the head 40 B and the other end secured to the said interior tube directly by a bar 17, as shown.

The device may be attached in operative position by screws in holes 20 through the head B, and a slide 21, adjustable by set-screw 22, on the inner body member.

By the constructions and combinations of parts two substantially closed air or fluid chambers are formed—a principal or main chamber H including the space inside the 50 two tubes or members bounded by the head B, the closure F and the packing, and a second chamber I including the space above the packing and below the head C and between the exterior and interior members—55 each of said chambers being of variable capacity as the interior tube is reciprocated relative to the exterior member.

To control the flow of air into and out of these chambers, in addition to the small 60 open space 16 before mentioned, adjustable valves may be provided, valve K located within an opening in the cap F, and valve L located within an opening in head C, the former being the main valve.

65 Obviously, when the inner telescopic mem-

ber is drawn out and the spring is expanded the control of the discharge of air from the chamber H will determine the degree of the checking or retarding effect upon the contracting spring and inwardly moving 70 telescopic member. Under like conditions the control of air entering the chamber I by valve L will determine the checking or retarding effect in a similar way. When the inner telescopic member is drawn out and 75 the spring expanded simultaneously air quite freely passes to chamber H from chamber I back of the piston and packing by way of the small opening 16, and also by way of the valve K. At the same time air 80 in chamber I can pass out through valve L. However, chamber I may be ignored when there is a very large opening or space for the passage of air to and from the same; and also when the inner body member is of 85 slightly less diameter than the outer body member, one air chamber only—chamber H—then being formed, as the control of the discharge of air from this chamber H is sufficient to secure the desired checking or 90 retarding effect. In briefer statement air enters chamber H quite freely while the inner member is being drawn out and the spring expanded, so there is substantially no retardation of movement, but when the 95 spring is automatically contracting and drawing the member inwardly the passage of air out of chamber H is restricted according to the area of the small discharge opening and there is a checking or retarding 100 of the movement. The inner member can thus be drawn out quickly without substantial retardation, but it moves inwardly slowly with retardation.

I have found that a permanent opening of 105 small area secures the desired retardation when the work to be done is constant, but when the period of time in which the work to be done varies or the device is to be applied to do different amounts of work the 110 adjustable valve works well and is preferably employed. Obviously, the adjustable valve K allows the degree of retardation to be controlled and the contractile energy of the spring to be utilized through different 115 periods of time.

In the example shown by Figs. 2 and 3 the letter A' designates an exterior hollow body member, in this instance a metallic tube of suitable length and diameter, provided with interior threads 1' and 2' at opposite ends; B', a substantially closing head at one end having exterior threads 3' matching the threads 1'; and C' a head at the opposite end with exterior threads 4' matching 120 the interior threads 2' of the tube, and provided with a central opening 5' constituting a bearing.

The head B' has an eye D' which is part 125 of the plug 6 having a hole 7 at one end for 130

attachment and threaded at the other end to engage the threads defining the opening 8 in the head.

5 E' designates an interior hollow body member, in this instance a metallic tube, provided with exterior threads 9' and slots 10' at the left hand end and with interior threads 11' at the other end, said tube being located and movable within the opening 5' 10 in head C' and projecting beyond the said head so it can be attached.

F' designates a threaded closure for the projecting end of tube E', in the form of a plug, and it engages the threads 11', the 15 plug having a hole 12 for attachment.

On the inclosed threaded end of the member E' is a hollow piston or plunger comprised of a hollow threaded ring or washer 13', a cup-shaped flexible packing 14' of 20 leather or other suitable material, and a threaded follower or clamping ring 15', the cup packing facing the head B' and adapted frictionally to engage the interior surface of member A' and form a tight joint when subjected to greater than atmospheric air pressure, but which packing can yield and allow 25 air to pass from the space back of it to the space in front of it. The ring 13' is of slightly less diameter than the tube A' so as 30 to provide a small open space 16' for the passage of air downwardly and between the packing and inner surface of the exterior member.

35 S' is a contractile helical spring located mainly within the interior tubular member when seated, the spring normally being slightly under tension, as shown, and secured at one end to the eye D' on the head B' and the other end secured to the said interior tube meditately through a threaded rod 18 and threaded washer 19 thereon carried by the plug which closes the end of the tube. When unscrewed from the tube, the plug and rod may be screwed into the 45 washer and the spring expanded to increase its tension or to take up possible slack due to permanent set.

50 It will be clear from the constructions and combinations of parts two substantially closed air chambers are formed—a principal or main chamber H' including the space inside the two tubes or members bounded by the head B', the closure F' and the packing, and a second chamber I' including the space 55 above the packing and below the head C' and between the exterior and interior members—each of said chambers being of variable capacity as the interior tube is reciprocated relative to the exterior member.

60 To control the flow of air into and out of these chambers, in addition to the small open space 16' before mentioned, a small open space 23 may be provided between the head C' and the interior tube, and also an 65 adjustable valve M located within the head

B', as shown, the same consisting of a threaded screw with part of the metal removed and adjustably seated within the hole in the head whereby the area of the air passage can be varied.

70

Obviously, when the inner telescopic member is drawn out and the spring is expanded the control of the discharge of air from chamber H' will determine the degree of the checking or retarding effect upon the 75 contracting spring S' and the inwardly moving telescopic member E'. The size of the opening 23 by which air can pass to chamber I' will also determine in a degree the checking or retarding effect. When the 80 inner telescopic member is drawn out and the spring expanded simultaneously air quite freely passes to chamber H' from chamber I' back of the piston and packing by way of the small opening 16', and also 85 by way of the valve M. At the same time air in chamber I' can pass out through the small open space 23.

However, chamber I' may be ignored when there is a very large opening or space 90 for the passage of air to and from the same; and also when the inner body member is of slightly less diameter than the outer body member, one air chamber only—chamber H'—then being formed, as the control of the 95 discharge of air from this chamber H' is sufficient to secure the desired checking or retarding effect.

In briefer statement, air enters chamber H' quite freely while the inner member E' 100 is being drawn out and the spring S' expanded, so there is no substantial retardation of movement other than overcoming the energy of the spring, but when the spring is automatically contracting and drawing the 105 member inwardly the passing of the air out of chamber H' is restricted according to the area of the small discharge opening and there is a checking or retarding of the movement. The inner member can thus be drawn out quickly without substantial retardation, but it moves inwardly slowly with retardation.

110 I have found that a permanent opening of small area from chamber H' secures the 115 desired retardation when the work to be done is constant, but when the period of time in which the work to be done varies or the device is to be applied to do different amounts of work an adjustable valve, like 120 M or otherwise, is preferably employed.

The adjustable valve allows the degree of retardation to be controlled and the contractile energy of the spring to be utilized through different periods of time.

125 To provide for an unretarded movement of the inner member and free contraction of the spring near the end of the inward travel the by-pass passage X may be formed in the outer member to allow air to pass from 130

chamber H' around the packing when the packing reaches a position between the ends of the by-pass. This insures the utilization of the entire remaining contractile energy 5 of the spring without substantial retardation which imparts an impulse to the momentum of the interior member.

Fig. 4 shows one of the many specific uses for which the device is adapted. 30 is a 10 semi-elliptic vehicle spring; 31, a part of a vehicle frame; 32, the outer body member of my device; 33, the interior member loosely supported in a bracket 34, as shown; 35, a lever device pivoted to a bracket 36 15 with one arm in pivotal connection with said telescopic interior member and the other arm pivoted to one end of the spring. The rocking of the lever reciprocates the interior member which is retarded in its 20 inward movement and acts as a shock absorber.

I am aware that devices have been designed comprising a piston, piston rod and helical spring inclosed within a cylinder, the 25 spring surrounding the piston rod back of the piston and with its ends loosely bearing against the piston and closed end of the cylinder, the spring in such devices being designed to do the work by expansive or 30 recoil energy after being compressed. Such devices are practical generally only when the elongation of the spring upon recoil after compression is limited to a relatively short distance or a few inches. Where the 35 travel of the parts to be actuated by the spring is much greater, such devices are impracticable, and attempts to remedy their defects by increasing the number of coils or the pitch of the coils or changing the elasticity of the wire constituting the coils, have 40 been found ineffectual and unsatisfactory for many reasons.

In distinction therefrom and as the result of extended experiments I employ the contractile energy of an expanded helical spring 45 of relatively light weight and small dimensions to do the required automatic work, which spring admits of expansion and contraction through a relatively great distance 50 and which can be inclosed within a small space out of sight and protected from rust and injury, the ends of the helical spring being attached to the parts which are to be actuated or moved one relative to the 55 other.

In my application for Letters Patent filed February 12, 1913, Serial No. 747,933, I have shown and described a combination of elements comprising a door, a door casing, 60 a contractile spring and retarding device, and attachments, all designedly coöperating and functioning to close and control the closing movement of the door. In the present application a part of the whole combination therein disclosed—the contractile

spring and retarding device only—is abstracted therefrom and separately claimed.

What I claim is:

1. The combination of two hollow telescopic body members the outer one substantially closed at both ends and one of said ends having a bearing for the inner member which latter is located and movable within the bearing, the outer end of the inner member being closed and the opposite 70 end open, a contractile helical spring within and connected to both members and normally holding them together, and means between the inner member and the inner surface of the outer member forming a substantially tight joint, whereby two substantially closed fluid chambers are formed between the members. 75

2. The combination of a hollow outer body member and a hollow piston rod telescopedly mounted within a bearing supported by the outer member, said outer member and hollow piston rod being closed at their extreme outer ends, a contractile helical spring within the hollow piston rod and outer member and connected at one end to said rod and at the other end to the outer member, and a hollow piston or plunger carried by the rod forming a substantially closed chamber of variable capacity. 80

3. The combination of telescoping inner and outer hollow body members, means for substantially closing the end of the outer member, a bearing for the inner member said inner member having an extension outside 90 and being movable within said bearing, means for forming a substantially tight joint between the members and with the outer member forming a substantially closed chamber of variable capacity, and a contractile coiled spring under tension within 95 and positively connecting and normally holding together the two members; means being provided for the admission of fluid to and its discharge from said chamber. 100

4. The combination of outer and inner telescopic hollow body members the inner one having an extension outside the other both substantially closed at their extreme outer ends the inner member having an open 115 end and both together forming a substantially closed variable fluid chamber, a concealed contractile helical spring within and positively connecting the members said spring when contracted holding the members together, and means adapted for attaching the members in operative position. 120

5. The combination of outer and inner telescopic hollow body members both substantially closed at their extreme outer ends the inner one having an open end and also having an extension beyond the other, means for forming a joint between the telescoping members and providing a substantially closed variable fluid chamber, a concealed 125

contractile helical spring inside and connected to the opposite members, and means adapted for attaching the members in operative position.

5 6. The combination of two telescopic tubes one extended beyond the other and adapted for attachment, a contractile helical spring within the tubes having its opposite ends connected to the opposite tubes and when 10 slightly under tension holding them together, and means for securing a gradual checking or retarding effect on the relative movement of the tubes when the tubes, relatively moved apart and the spring expanded, 15 are forced together by the contractile energy of the spring.

7. The combination of two telescopic tubes one extended beyond the other and adapted for attachment, a contractile helical spring 20 within the tubes having its opposite ends connected to the opposite tubes and when slightly under tension holding them together, and means for securing different retarding effects or speeds when the tubes, 25 relatively moved apart and the spring expanded, are forced together by the contractile energy of the spring.

8. The combination of telescopic hollow body members the end of one being extended 30 beyond the other for attachment, a contractile helical spring under tension within and its opposite ends connected respectively to the opposite members and normally holding them together, and means, when the 35 members are moved apart and the spring expanded, acting in opposition to the spring and retarding the contractile energy of the same.

9. The combination of inner and outer 40 telescopic hollow body members, the inner one extended outside the other and both substantially closed to form a variable fluid chamber, a contractile helical spring within and positively connecting the two members, 45 and means for permitting the passage of fluid into and its gradual passage out of said chamber to obtain a retarding effect.

10. The combination of telescoping inner 50 and outer hollow body members the inner one extending beyond the other for attachment, a packing forming with said members a substantially closed variable fluid chamber, a spring within positively connecting the two members and normally holding them 55 together, means for allowing fluid quite freely to pass out of said chamber when the members are moved apart and the spring expanded, and means for checking the contractile energy of the spring and retarding 60 the inward movement of one member relative to the other.

11. A combined contractile spring and retarding device, including telescopic body members one of them tubular and having an extension beyond the other, a packing sup-

ported by one of the members and forming with the members a substantially closed variable air chamber, a contractile helical spring within and connecting the members, and means adapting the device for attachment; 70 said device having an air passage or opening of relatively small sectional area designed for the restricted discharge of air from the chamber to secure a checking or retarding effect when the members relatively 75 telescope together under the contractile energy of the spring.

12. A combined contractile spring and retarding device, including tubular body members telescopically mounted one within the 80 other the outer ends being substantially closed, a contractile helical spring within and positively connecting said opposite members, a packing secured upon the inner body member, a valve in connection with 85 one of the members, and means adapting the device for attachment.

13. A combined contractile spring and retarding device, including two telescopic tubular body members, one having an extension beyond the other, closed to provide 90 a variable air chamber, means for admitting air to the chamber, means for restricting the passage of air out of said chamber for the purpose set forth, and a contractile helical 95 spring within and connecting the inner and outer members.

14. The combination of telescopic outer and inner members, the interior member having an extension beyond the end of the 100 other for attachment; an inside concealed contractile helical spring with its opposite ends connected to the opposite members and when contracted holding them together; a fluid chamber of variable capacity in operative connection with the members; and means for allowing the gradual variation of the quantity of fluid in the said chamber to secure a retarding effect when the members, 110 relatively moved apart and the spring expanded, are relatively forced together by the contractile energy of the spring.

15. The combination of telescopic outer and inner members, the interior member having an extension beyond the end of the 115 other for attachment; an inside concealed contractile helical spring with its opposite ends connected to the opposite members and when contracted holding them together; a fluid chamber of variable capacity in operative connection with the members; and adjustable means for allowing different gradual variations of the quantity of fluid in the said chamber to secure different retarding effects when the members, relatively moved 120 apart and the spring expanded, are relatively forced together by the contractile energy of the spring.

16. The combination of telescopic outer and inner members having in operative con- 130

nection therewith a substantially closed fluid chamber of variable capacity, the interior member having an extension beyond the outer for attachment and carrying a 5 piston or plunger located and movable within the said chamber; and an inside concealed contractile helical spring positively attached to opposite members and when contracted holding them together; and said piston or plunger gradually varying the quantity 10 of fluid in the chamber to secure a retarding effect when the members, relatively moved apart and the spring expanded, are relatively forced together by the contractile 15 energy of the spring.

17. The combination of outer and inner telescopic members, the inner member having an extension beyond the other adapting it for exterior attachment; means for forming 20 a substantially closed variable fluid chamber in operative connection with the members; a concealed contractile helical spring within and connecting the members and normally holding them together; means for 25 gradually varying the quantity of fluid in the chamber and allowing its free passage in one direction but retarding its flow in the other direction, whereby the relative outward movement of the inner member is free 30 and its reverse movement retarded.

18. The combination of outer and inner telescopic body members one member being tubular and having an extension beyond the other for attachment; a contractile helical 35 spring inside the tubular member with one end secured thereto and the other end extended and secured to the other member and normally holding said members together; and a fluid chamber of varying capacity in 40 operative connection with said members; said tubular member having a piston or plunger located and movable within said fluid chamber to secure a retarding effect upon the spring when contracting and moving 45 the members relatively together.

19. The combination of exterior tubular and interior telescopic members the interior member having an extension outside the other for attachment; a fluid chamber inside 50 said exterior member; a contractile helical spring also inside and having its opposite ends connected respectively to the opposite members; and a piston or plunger carried by the interior member and located and movable within the said chamber; all for the purpose set forth.

20. The combination of two telescopic body members, the interior one being hollow to receive a spring and extended beyond the other for attachment, substantially closed to form an air chamber of variable capacity; a contractile helical spring within and connected to the opposite members and when contracted holding them together; and 65 means for gradually varying the quantity

of air within the chamber to secure a checking or retarding effect when the members, relatively moved apart and the spring expanded, are forced together by the contractile energy of the spring.

21. The subject-matter of claim 20 when the means bounding the air chamber has a relatively small opening restricting the passage of the air sufficiently to secure the desired retarding effect.

22. The subject-matter of claim 20 when the means for varying the quantity of air in the chamber consists of an adjustable valve device to secure different retarding effects.

23. The subject-matter of claim 20 with 80 the addition of means between the body members to form a sufficiently tight joint to retain air in the chamber.

24. The subject-matter of claim 20 with the addition of a packing and a ring engaging the packing and interior member and constituting a hollow piston or plunger for the passage of the spring.

25. The subject-matter of claim 20 with the addition of means for allowing air to 90 quite freely pass to the air chamber when its capacity increases.

26. The subject-matter of claim 20 with the addition of a packing which allows air to pass from the space above the packing 95 and into the space below the packing when the members telescope apart and vice versa when the members telescope reversely.

27. The subject-matter of claim 20 with the addition of means for taking up slack 100 or varying the tension of the spring.

28. The subject-matter of claim 20 with the addition of means for suddenly reducing the air pressure in chamber H' and unchecking the spring to increase the momentum of the interior member as it approaches its seat.

29. The subject-matter of claim 20 with the addition of a detachable head at the outer end of one of the members to allow 110 the attachment of one end of the inserted spring.

30. The combination of two telescopic body members one of them hollow to receive a spring and to form a substantially closed variable air chamber between the members in all their relative positions each of said members being provided with means adapting it for separate pivotal attachment, and a contractile helical spring within the 115 hollow member and connected with each of said members; there being provided in connection with said members an opening of relatively small sectional area for the gradual passage of air to secure a retarding or cushioning effect when the members moved apart and the spring expanded are telescoped together by the contractile energy of the spring.

31. The combination of telescopic outer 130

and inner members, the outer member being hollow closed at one end and having an opening at the other to receive the inner member which constitutes a reciprocating 5 plunger, said members forming a substantially closed fluid chamber of variable capacity but having in connection therewith means for allowing the passage of fluid to and its passage from said chamber, an inner 10 side concealed contractile helical spring one end positively attached to the outer member and the other end positively connected with the inner member and when contracted holding the members together; 15 and said inner member acting as a plunger gradually varying the quantity of fluid in the chamber to secure a retarding effect when the members relatively moved apart and the spring expanded are relatively 20 forced together by the contractile energy of the spring.

32. The combination in a retarding de-

vice, of two telescopically movable body members, the outer member having a bearing at one end for the inner member and 25 substantially closed at the other end, said inner member carrying a yieldable packing forming with the outer member an air chamber of variable capacity and said packing when subjected to pressure greater than 30 atmospheric pressure making a substantially tight frictional joint between the members, and a contractile helical spring with its axis in line with the axes of the 35 said members and its opposite ends secured to the opposite members and holding the members together; the means forming the air chamber being so designed and constructed that when the members are moved apart and the spring expanded the flow of 40 air from the chamber will be restricted and retarded to retard the inwardly telescopic movement.

EDWARD S. COFFMAN.
